US0D1052892S

(12) United States Design Patent (10) Patent No.: US D1,052,892 S
(45) Date of Patent:  Dec. 3, 2024

(54) SHOPPING BAG

(71) Applicant: HERMES SELLIER (Société par actions simplifiée), Paris (FR)

(72) Inventor: Pierre-Alexis Dumas, Paris (FR)

() Term: 15 Years

(21) Appl. No.: 35/519,823

(22) Filed: Jun. 23, 2023

(80) Hague Agreement Data

Int. Filing Date: Jun. 23, 2023

Int. Reg. No.: DM/230063

Int. Reg. Date: Jun. 23, 2023

Int. Reg. Pub. Date: Jan. 26, 2024

(51) LOC (14) Cl. 03-01

(52) U.S. Cl.

USPC D3/246; D3/306
